UNITED STATES PATENT OFFICE.

EDWARD A. SCHOOLEY, OF PITTSBURGH, PENNSYLVANIA, ASSIGNOR TO THE EASTERN RAILWAY SIGNAL COMPANY, OF PITTSBURGH, PENNSYLVANIA, A CORPORATION OF DELAWARE.

RAILWAY-TORPEDO.

1,359,924.

Specification of Letters Patent. Patented Nov. 23, 1920.

Application filed August 31, 1916. Serial No. 117,819.

To all whom it may concern:

Be it known that I, EDWARD A. SCHOOLEY, a citizen of the United States, and resident of Pittsburgh, in the county of Allegheny and State of Pennsylvania, have invented certain new and useful Improvements in Railway-Torpedoes, of which the following is a specification.

My invention relates to the construction of explosive railway torpedoes used as audible signals on railways, arranged to be secured in place on the head of the railway track rails and adapted to be exploded by contact with the wheels of locomotives or other rolling stock passing over the railway tracks.

One object of my invention is to provide a torpedo of the class described having novel means whereby the explosive material is packaged and the component parts of the torpedo are assembled and secured in assembled position in forming the torpedo.

Another object of the invention is to provide a torpedo of improved construction and having novel means whereby ingress of moisture to the explosive material is avoided and prevented.

A further object of my invention is to provide a railroad torpedo in which the use of metal in forming the package is avoided and rendered unnecessary, a fibrous package is obtained, and the liability of explosions and resulting damage in assembling the package is lessened and overcome.

A still further object of the invention is the provision of a railroad torpedo having the novel constructions, combinations, and arrangements of parts shown in the drawings, to be fully described hereinafter and specifically pointed out in the appended claims.

Referring now to the drawings forming part of this specification, Figure 1 is a plan showing a torpedo constructed and arranged in accordance with my invention.

Fig. 2 is a sectional side elevation of the same, the section being taken on the line II-II of Fig. 1.

Fig. 3 is a plan, similar to that of Fig. 1, showing a modified form of torpedo constructed in accordance with this invention.

Fig. 4 is a sectional side elevation of the modification shown in Fig. 3, the section being taken on the line IV-IV of Fig. 3.

Fig. 5 is a sectional side elevation of the modified form of torpedo shown in Figs. 3 and 4, the section being taken on the line V-V of Fig. 3.

Fig. 6 is a side elevation of the torpedo illustrated in Figs. 3, 4, and 5.

Fig. 7 is a sectional side elevation similar to Figs. 2 and 4 showing a further modification in the construction of torpedoes made in accordance with my invention.

In the accompanying drawings the numeral 2 designates the explosive material of the torpedo, which may be composed of any of the various known compositions, the explosive being in the form of a disk or button, or in a finely divided state, as proves most desirable or necessary. The explosive is positioned in a cup-shaped container 3 having a cylindrical side wall integrally joined to a bottom 4, which is flat as shown in Figs. 2 and 4 or hemispherical as shown in Fig. 7, the container being premolded and composed of paper, strawboard, or similar fibrous, non-metallic material. In the construction of Figs. 2 and 4 a second cup-shaped member 5 having a cylindrical side wall formed integrally with a top or end 6 is employed to form a cap for the container 3, the side walls of the container and its cap being in close engagement, so as to fit tightly and entirely inclose the explosive, and when the explosive is in a finely divided state, to prevent escape of particles of the explosive and ingress of moisture. The surfaces of the container and its cap may be coated with paraffin or similar material when found necessary or considered advisable.

The package comprising the container 3, cap 5, and explosive 2 is secured within a holder 7 which also is formed of paper, or other fibrous material, and a flat strap 8 formed of lead or other ductile metal is secured to the holder, this metal strap being employed to permit of the torpedo being easily and quickly attached to the head of a rail in a railway track in position for use, and when found necessary, to enable the torpedo being readily removed in condition to again be applied to the rail of a railway track.

The holder 7 may have a bottom 9 joined integrally to its cylindrical side wall, as shown in Fig. 2, or the bottom 9 may be omitted and the torpedo formed as is shown

in Figs. 4 and 5. In the construction of Figs. 1 and 2 one end of the holder 7 is crimped or beaded so as to turn the end of the holder inwardly from the position shown in dotted lines in Fig. 2 into that shown in full lines, the inturned end of the holder being brought into engagement with the periphery of the flat fiber disk 10 which rests on the top 6 of the cap 5 so as to securely hold the parts in assembled position.

In the construction shown in Figs. 1 and 2 the flat cylindrical disk 10 forming part of the holder is placed in position before the end of the holder 7 is crimped or turned inwardly, so that after the crimping operation the disk 10 will be fastened in place and will maintain the ductile metal strap 8 in position.

The metal strap 8 projects through the radial slots or grooves 11 in the periphery of the disk 10 in the construction shown in Figs. 1 and 2, as will be readily seen in these figures.

In some cases the radial slots 11, 11^a, in the periphery of the disk 10 may be omitted and the metal strap 8 which is used to fasten the torpedo in place on the railway track will project through slots 12 in the side wall of the holder 7 in the manner shown in Figs. 3, 4, 5, and 6. Otherwise the parts will be assembled as has been described, the edge of the holder being turned inwardly or crimped after the parts have been positioned within the holder. When the metal strap 8 is caused to extend through slots 11 in the side wall of the holder 7 the fiber disk 10 may be dispensed with, although preferably it will be employed in the construction of Figs. 3 and 4.

In the construction illustrated in Fig. 7 the explosive 2^a, preferably a pre-molded disk or button, is placed within the container 3^a. This container is formed of fibrous material, the same as those of Figs. 2 and 4 and has a peripheral flange 14 joined integrally to the bottom 4^a of the container. The container is hemispherical or dome shaped in cross section instead of being flat as in the containers of Figs. 2 and 4.

After the explosive is placed within the container, a cap 5^a formed of a flat disk or fiber or fibrous material is placed within the container and the flat metal strap 8 is then positioned in the container. A second flat fiber disk 10^a is placed in the container on top of the flat metal strap, the metal strap projecting through the radial slots or grooves 11 in the periphery of the disk 10^a as in the construction of Figs. 1 and 2. The end of the flange 14 on the holder 3^a of Fig. 7 is then crimped or turned inwardly from the position shown dotted into that shown in full lines to fasten the parts securely in assembled position, in the same

manner as has been described in connection with the other figures. Obviously the metal strap may be caused to extend through openings in the flange of the container 3^a in the same manner as shown in Fig. 4 when found necessary or desirable.

When a tubular holder 7 is employed instead of a holder having an integrally formed bottom 9 both edges of the holder will be crimped inwardly in the manner shown in Figs. 4 and 5. It will be readily understood that the tubular holder may be employed with the construction of Figs. 1 and 2 as well as that of Figs. 3, 4, 5, and 6.

Some railways prefer to employ a tread strap 13 on the torpedoes (see Figs. 1 and 2), the tread strap which is formed of soft metal, such as zinc or lead, being adapted to engage with the wheels of the rolling stock and prevent the torpedo sliding forwardly on the track rail when engaged by the advancing wheel. In most cases, however, the tread strap will be omitted. When used, the tread strap 13 will project through the slots 11^a—11^a in the disk 10 of Figs. 1 and 2, or through slots 12^a—12^a in the side wall of the holder 7 of Figs. 3 and 4, and as the tread strap 13 extends lengthwise parallel with the rail it will rest on top of the rail head so that the wheels of the rolling stock will ride over the tread strap and prevent the torpedo sliding on the rail.

The advantages of my invention will be apparent to those skilled in the art. By forming torpedoes of fibrous material and by assembling and securing the assembled parts of the torpedoes in the manner shown and described, a cheap, strong, and durable torpedo is provided.

The torpedoes are easily and quickly made and the liability of premature explosions in forming the torpedo is reduced to a minimum.

Modifications in the construction and arrangement of the parts may be made without departing from my invention as defined in the appended claims. The cross section of the container may be varied. The fibrous caps forming part of my improved package may be cup-shaped as shown in Figs. 3 and 4 or may be flat disks as in Fig. 7, and other changes may be made within the scope of the claims.

I claim:—

1. A railway torpedo comprising an explosive charge, coacting cup-shaped members formed of fibrous material and arranged to inclose said explosive charge, a ductile metal strap on one end of the package formed by said members, said strap having projecting ends forming a rail engaging fastener for the torpedo, a disk of fibrous material on top of said strap and a holder formed of fibrous material and surrounding said cup-shaped members, said

holder having an inwardly flanged end to secure the parts in assembled relation.

2. A railway torpedo comprising an explosive charge, coacting cup-shaped members formed of fibrous material and arranged to inclose said explosive charge, a ductile metal strap on one end of the package formed by said cup-shaped members, said strap having projecting ends forming a rail engaging fastener for the torpedo, a disk of fibrous material on top of said strap and a holder formed of fibrous material and surrounding said cup-shaped members, said holder having apertures therein through which the projecting ends of said metal strap extend, and said holder having an end flanged inwardly to secure the parts in assembled relation.

3. A railway torpedo comprising an explosive charge, coacting cup-shaped members formed of fibrous material and arranged to inclose said explosive charge, a ductile metal strap on one end of the package formed by said cup-shaped members, said strap having projecting ends forming a rail engaging fastener for the torpedo, a disk of fibrous material on top of said strap and a holder formed of fibrous material and surrounding said cup-shaped members, said holder having its ends flanged inwardly into fastening engagement with the cup-shaped members to secure the parts in assembled relation.

4. A railway torpedo comprising an explosive charge, a fibrous cup-shaped member forming a container for said charge, a fibrous member forming a casing surrounding said cup-shaped container, and a ductile metal strap on top of said container having projecting ends forming a rail engaging fastener for the torpedo, said casing having a concentric inwardly extending flanged end, with the edge of the concentric end engaging with said container to secure the parts in assembled relation.

5. A railway torpedo comprising an ex-

plosive charge, a fibrous cup-shaped member forming a container for said charge, a fibrous holder forming a casing surrounding said cup-shaped member, a ductile metal strap on top of said container having projecting ends forming a rail engaging fastener for the torpedo, said holder having apertures through which the ends of said metal strap project, and a fibrous disk on top of said strap to hold the strap in place, said holder having an inwardly flanged end engaging with said disk to maintain the parts in assembled relation.

6. A railway torpedo comprising an explosive charge, a fibrous holder, a fibrous cap, and a ductile metal strap having projecting ends forming a rail engaging fastener for the torpedo, the end of said holder being crimped and extending concentrically inward with the edge of the concentric end in tight holding engagement with the cap to secure the parts in assembled relation.

7. A railway torpedo comprising an explosive charge, a fibrous holder, a fibrous cap, and a ductile metal strap having projecting ends forming a rail engaging fastener for the torpedo, and a flat fibrous disk on top of the metal strap, the end of said fibrous holder being crimped and extending inwardly into tight holding engagement with said flat disk to secure the parts in assembled relation.

8. A paper torpedo comprising an outer cup-shaped paper case, an inner cup-shaped paper case telescoping the outer case and placed in an inverted position therein, the flange of the outer case being considerably deeper than the flange of the inner case, and a strap-carrying member placed within the outer case and against the bottom of the inner case, the edge of the flange of the outer case being doubled inward against the strap-carrying member for the purpose described.

In testimony whereof I have hereunto set my hand.

EDWARD A. SCHOOLEY.
